G. J. May of Wallingford, Conn.

Letter Patent No. 2328 Dated May 29, 1866

Design for a Spoon or Fork handle

The schedule referred to in these Letters Patent and making part of the same.

To all whom it may concern:

Be it known that G. J. May, of Galesville, in the Town of Wallingford, County of New Haven, and State of Connecticut, have invented a new Design for the shanks of Spoons, Forks, Ladles, and Butter Knives; and I do hereby declare that the following is a full, clear and exact description of the same, reference being had to the accompanying drawings forming part of this specification in which

Figure 1, is a face view of a spoon of any design.

Figure 2, is a central longitudinal section of the same.

Figure 3, is a transverse section of the shank in the plane indicated by the line, x, x, in Figure 1.

Figure 4, is a transverse section of the bowl near its junction with the shank in the plane indicated by the line, y, y, in Figure 1.

Figure 5, is a transverse section of the shank in the plane indicated by the line, z, z, in Figure 1.

Figure 6, is a back view of the spoon.

Similar letters of reference indicate corresponding parts in the several figures.

The spoon has its shank swelled very much thicker than is usual in a direction perpendicular to the face at a point not far distant from its junction with the bowl as shown at, a, in Figure 2, and from this swelled and thickest point it diminishes in thickness toward the head.

2

D.S. 2328

swelled and thickest point, it diminishes in thickness toward the head and also toward the bowl, the diminishing swell being continued into the bowl in such manner as to make the bowl thicker in the centre of its width than at its sides, as shown in Figure 4, for some distance from the shank. The transverse section of the thick portion of the shank presents on its face a nearly flat surface and on its back a rounded or half round surface as shown in fig 3.

The roundness of the back is diminished toward the bowl and the head of the spoon, the transverse section of the head being nearly flat.

The representation and description of the spoon is sufficient to illustrate my design, as the entire shank and handle will be of precisely the same form through the whole service consisting of spoons, ladle, forks and butter-knives. The swelled part of the shank, a, tapering into the pronged part of the fork, and the blade of the knife in the same manner as into the bowl of the spoon or ladle.

What I claim as my invention and desire to secure by Letter Patent is: The design for the shank of a spoon, ladle, fork or butter-knife herein described and represented in the accompanying drawings.

Witness,

W. Lebbe

J. W. Combe

G. A. May.
